UNITED STATES PATENT OFFICE

2,374,174

APPARATUS FOR PILING METALLIC SHEETS

Dario Buccicone, Gary, Ind., assignor to Carnegie-Illinois Steel Corporation, a corporation of New Jersey

Application October 22, 1942, Serial No. 462,997

3 Claims. (Cl. 214—11)

This invention relates to the piling of metallic sheets and particularly to an improved apparatus for and method of piling the same.

In the steel industry it has been a difficult problem to pile metallic sheets mechanically in a rapid and efficient manner without damaging the same, especially the larger size sheets. Heretofore, various types of pilers and conveyors have been suggested and used for piling such sheets but they were unsatisfactory for the reason that they tended to scratch or bend the sheets which of course was undesirable. In addition to scratching, bending or otherwise damaging the sheets, it was impossible in the pilers heretofore suggested and used to discard substandard or damaged sheets without stopping the piler or conveyor system and manually removing such sheets so as to separate them from the standard sheets.

Accordingly, it is the general object of the present invention to provide an improved apparatus for and method of piling metallic sheets which is efficient and effective in use and by which the sheets can be rapidly piled without damaging the same, thereby eliminating the above-mentioned disadvantages.

It is another object of this invention to provide an improved apparatus of piling metallic sheets which is simple and inexpensive in its construction, and at the same time apparatus which is easy and convenient to use.

It is a more specific object of this invention to provide an improved apparatus for piling metallic sheets wherein the sheets are held in a suspended position by a magnetic means, conveyed to a predetermined point while held in such suspended position and dropped and guided to a point therebelow so that the sheets are neatly piled one on top of the other, thereby avoiding any danger of scratching and bending of the sheets.

It is a further object of my invention to provide an improved apparatus for and method of piling metallic sheets wherein the sheets can be continuously conveyed to any predetermined point and dropped therefrom so as to be piled one on top of the other, so that the standard sheets can be separated from the substandard sheets while the sheets are being conveyed.

It is still another object of the present invention to provide an apparatus for piling metallic sheets wherein relatively large sheets can be piled thereby as well as relatively small sheets, thereby providing apparatus which is extremely flexible in its use.

Various other objects and advantages of this invention will become more apparent during the course of the following specification and will be particularly pointed out in the appended claims.

In the accompanying drawings there is shown, for the purpose of illustration, one embodiment which my invention may assume in practice.

In the drawings:

Figure 1 is a side elevational view of the improved sheet piling apparatus of my invention;

Figure 2 is an end elevational view of the same;

Figure 3 is a plan view thereof;

Figure 4 is a sectional view taken on line IV—IV of Figure 3;

Figure 5 is a vertical section through one of the magnets in the rear end of my improved apparatus;

Figure 6 is a vertical section similar to Figure 5 through one of the magnets in the front end of my apparatus; and

Figure 7 is a wiring diagram showing how the magnets and switches are connected in the electrical circuit.

Referring more particularly to the drawings, there is shown a conventional type roller conveyor 2 having rollers 3 and which is supported by legs 4. This conveyor is positioned preferably at the end of the flying shear line from which the metallic sheets are cut to length and delivered therefrom in a manner well known to those in the steel industry.

According to the present invention, there is arranged at a spaced distance above the roller conveyor 2, a pair of spaced apart rows 5 of electro-magnets 6. The magnets 6 in each of the rows 5 are spaced from each other preferably by means of spacing members 7. The spacer members 7 and magnets 6 are connected to each other so as to provide a longitudinally extending rigid unit or row of magnets. The two rows or units 5 are supported preferably by a pair of overhanging arms 8 and the arms are in turn supported preferably by a pair of upwardly extending structural or I-beam members 9 arranged to one side of the roller conveyor 2. Below the roller conveyor 2 there is arranged preferably a movable base member 10 which supports the upwardly extending I-beam members 9. The base 10 is preferably mounted on wheels or rollers 12 for moving the base together with the magnets away from the roller conveyor when it is desired not to use the same.

Along the bottom of each of the rows or units

5 of the magnets 6, there is arranged preferably a longitudinally extending shoe 13 which is made preferably of brass. In other words, the shoes 13 extend throughout the length of the rows or units 5 below the magnets 6. The brass shoes 13 are held in position by the cores 14 of the magnets which extend through the brass shoes as shown in Figures 5 and 6 of the drawings. The cores 14 are held in position in their respective magnets preferably by means of cap screws 15 which extend through a hole in the top of the metal housing 16 of the magnets 6.

There is provided a plurality of conventional rubber and fabric or leather V-belts 17 for conveying the metallic sheets along while the sheets are held in suspended position by the magnets 6. While one V-belt arranged longitudinally along each row of magnets 6 would serve the purpose, in the present instance, there are shown two V-belts at the front end of the rows or units 5 and only one belt at the rear end thereof. There is arranged in suitable bearing preferably at the front end of the rows or units 5 and extending therebetween and to one side thereof, a drive shaft 18. At the front end of each row or unit 5 and directly opposite thereto there is mounted on the shaft 18, a pair of pulleys 19 over which the V-belts 17 at the front end of the apparatus are disposed. Intermediate the length of each row of magnets or units 5 there is arranged a pulley 20 around which the V-belts 17 are disposed and there is provided above each row or unit between the pulleys 19 and the pulleys 20 thereof, an idler pulley 21 over which the V-belts also pass. The V-belts 17 in the front part of the assembly, as shown in Figure 6 of the drawings, are disposed in V-shaped grooves or slots 22, arranged in the brass shoes 13 to either side of the cores 14 of the magnets, and the V-belt 17 at the rear end of the piler is disposed in a V-shaped groove arranged in the bottom of each of the cores 14 of the magnets centrally thereof, as shown in Figure 5. It will be understood that the bottom or outer side of the V-shaped belts 17 is disposed a slight distance below the bottom of the brass shoes 13 and the cores 14 of the magnets so that the metallic sheets will not contact the shoes or magnets directly as they are moved therealong by the V-belts. The V-belts at the rear end of each of the rows or units 5 are disposed around the pulleys 20 which drive the same and pass over and around similar pulleys 23 arranged at the extreme end of each of the rows or units 5. There is also provided an idler roller 24 arranged above each of the rows or units 5 between the pulleys 20 and 23 in a manner similar to the idler pulley 21. Any suitable means may be provided for adjusting the tautness of the belts 17. It is preferred that one of the pulleys over which the belts are disposed be movable so that the belts may be kept reasonably taut at all times.

On the outer end of the drive shaft 18 there is disposed preferably a sprocket 25 over which a chain 26 is disposed. There is mounted preferably on the base 10 a motor 27 having a sprocket 28 arranged on the shaft thereof over which the chain 26 is also disposed. It will be understood that it is the purpose of the motor 27 to drive the V-belts 17 through the action of chain 26, sprocket 25 and pulleys 19 and 20. The motor 27 is controlled preferably by a switch 29 and a rheostat 30 arranged on the front or to one side of the pair of rows of magnets or units 5 as shown in Figure 1 of the drawings.

Between the two rows of magnets or units 5,

there is arranged substantially parallel thereto preferably a longitudinally extending angle-iron member 31 which is adapted to act as a trackway or guide. There is positioned on the angle-iron member or track 31, a limit switch 32 which is adapted to be moved along and disposed at any position along the trackway 31 for a purpose hereinafter to be described. There is carried by the limit switch 32 a downwardly extending switch-actuating member 33 which extends a slight distance below the bottom of the brass shoes 13 and the V-belts 17 as shown in Figure 1. The limit switch 32 as shown in the wiring diagram of Figure 7 is disposed in the main circuit for controlling the energization of the magnets 6.

There is also arranged on the front or to one side of the rows of magnets preferably a plurality of push switches 34 for controlling the energization of the magnets; that is, the switches are used to cut into or out of the circuit various magnets to compensate for variable lengths of sheets it is desired to convey and pile. These switches 34 are arranged in the electric circuit as shown in the wiring diagram of Figure 7.

25 Directly below the rows of magnets or units 5 on the roller conveyor 2, there is suitably disposed a plurality of vertically extending sheet guides 35 for the purpose of guiding the sheets to the top of the conveyor or pile after they have 30 been released by, and dropped from the magnets 6. In other words, there is a guide 35 positioned to either side of the pile so as to align the sides of the sheets and to guide the same as they are dropped from the belts 17 and there is also arranged a guide 35 at either end of the pile for 35 guiding and aligning the ends of the sheets as they are dropped from the magnets. It will be understood that these guides are so constructed and arranged that they may be adjusted to any 40 desired position along the roller conveyor and to any point beneath the magnets. The end guides are arranged so that they may be moved away from the end of the pile of sheets so as to permit the pile to be conveyed along the roller conveyor after a desired number of sheets have been piled.

The improved sheet piling apparatus of my invention functions in the following manner. The sheets are delivered from the flying shear line preferably over a belt conveyor 36 which is disposed directly opposite the forward end of the row of magnets or units 5. The top of the belt conveyor 36 is preferably spaced a slight distance below the bottom of the V-belts 17 of my improved piling apparatus as shown in Figures 1 and 4 of the drawings. As the sheets are delivered from the flying shear line over the belt conveyor 36 they pass in under the electro-magnets 6, the brass shoes 13 and the V-belts 17. The circuit to the electro-magnets 6 having been closed, the magnets are now energized and the sheets as they are delivered from the conveyor belts 36 are drawn upwardly by the magnetic force of the magnets 6 against the bottom side of the V-belts 17. The circuit to the motor 27 having been closed and the V-belts set in operation, the sheets are conveyed along by the V-belts 17 while they are held in such suspended position by the magnets 6. Before the delivery of the sheets to the apparatus has been started, the guides 35 are set at the proper position on the roller conveyor 2 and the limit switch 32 is positioned at the proper point along the rows of magnets. As the sheets are conveyed along the rows of magnets by the V-belts 17 they successively strike the downwardly extending finger-like actuating member 33 of the

limit switch 32 so as to open the circuit to the magnets, thereby deenergizing the same. Due to the fact that the magnetic force of the magnets no longer exists due to the deenergization thereof, the sheets drop from the bottom of the V-belts 17 down between the guides 35 and onto the roller conveyor 2 and the top of the pile of sheets between the guides. It will be seen that as the sheets drop from the V-belts 17 they are maintained in substantially a horizontal plane and drop in a perfectly flat condition upon the roller conveyor and the pile of sheets.

It will be understood that the guides 35 may be positioned at the forward end of the conveyor and the standard sheets may be made to drop on the magnets at that point. However, if the operator notices a sheet which is not up to standard he can close push switch 29 which cuts all of the magnets into the circuit as shown in Figure 7 of the drawings, thereby energizing the same, and maintains them in action so that the magnets will not be deenergized when such sheet strikes the actuating finger member 33 of the switch 32. Such substandard sheet will then be carried to the end of the rows of magnets or units by the V-belts 17 and piled on top of the roller conveyor 2 at a point removed from the location of the pile of standard sheets.

As the result of my invention it will be seen that there is provided apparatus which is simple in its construction and use and at the same time apparatus which neatly and efficiently piles the sheets one on top of the other. It will also be seen by the use of my improved apparatus that the substandard sheets may be easily and conveniently separated from the standard sheets and conveyed to a point removed from the pile of standard sheets without the need of manual handling of the same.

While I have shown and described one specific embodiment of my invention, it will be understood that this embodiment is merely for the purpose of illustration and description and that various other forms may be devised within the scope of my invention, as defined in the appended claims.

I claim:

1. Apparatus for conveying metallic sheets, including longitudinally extending magnetic means for receiving and holding the sheets in a suspended position as they are delivered thereto, said magnetic means having a longitudinally extending nonmagnetic shoe at the bottom thereof, a relatively narrow longitudinally extending groove

arranged in the bottom of said shoe, a relatively narrow nonmagnetic conveyor belt arranged in said groove with the lower side thereof disposed a slight distance below said magnetic means for conveying the sheets along while they are held in a suspended position by said magnetic means, means for driving said conveyor belt, and means arranged below said magnetic means and said belt for receiving the sheets as they are released by said magnetic means.

2. Apparatus for conveying metallic sheets including a plurality of horizontally aligned, spaced apart, electrically energized magnets for receiving and holding the sheets in a suspended position as they are delivered thereto, a longitudinally extending nonmagnetic shoe at the lower end of said magnets and extending therebetween, a relatively narrow longitudinally extending groove arranged in the bottom of each of said magnets, a relatively narrow nonmagnetic V belt arranged in and extending through the groove of each of said magnets with the lower side of said belt positioned a slight distance below each of said magnets for conveying the sheets along while they are held in a suspended position by said magnets, means for driving and means for tensioning said conveyor belt, and means arranged below said magnets and said belt for receiving the sheets as they are released by said magnets.

3. Apparatus for conveying metallic sheets including at least two rows of horizontally aligned, spaced apart, electrically energized magnets for receiving and holding the sheets in a suspended position as they are delivered thereto, longitudinally extending nonmagnetic shoes at the lower end of said rows of magnets and extending longitudinally therebetween, a longitudinally extending groove arranged in the bottom of each of said magnets, a relatively narrow nonmagnetic V-belt arranged in and extending through the groove of each of said magnets with the lower side of said belt positioned a slight distance below each of said magnets for conveying the sheets along while they are held in a suspended position by said magnets, means for driving and means for tensioning said conveyor belt, trigger means operable by said sheets as they are moved along to deenergize said magnets to release said sheets, means arranged below said magnets and said belt for receiving the sheets as they are released by said magnets, and means to render said trigger means ineffective whereby selected sheets will not be released above said sheet receiving means.

DARIO BUCCICONE.
